Primary Examiner — Sheryl Lane*Assistant Examiner* — Nicole Shiflet(74) *Attorney, Agent, or Firm* — Birch, Stewart, Kolasch & Birch, LLP(57) **CLAIM**

We claim the ornamental design for an oven range, as shown and described.

DESCRIPTION

FIG. 1 is a perspective view of an oven range showing our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a perspective view of an oven range, showing a second embodiment of our new design.

The broken lines in the drawing figures are included for the purpose of illustrating environment and form no part of the claimed design. FIG. 8 is the only view showing the second embodiment. Therefore, the second embodiment includes only what is shown in FIG. 8.
